MANUFACTURE OF MELAMINE

Andrews C. Wintringham, Glen Ridge, and Victor L. King, Bound Brook, N. J., assignors to American Cyanamid Company, New York, N. Y., a corporation of Maine.

Application May 28, 1941, Serial No. 395,586

3 Claims. (Cl. 260—248)

This invention relates to the manufacture of melamine from cyanamide or dicyandiamide. More particularly, the invention deals with an improvement in a process for the production of melamine of high purity which is described in an application of Victor L. King, Serial No. 344,638, filed July 10, 1940, and in a modification of that process which is described in our copending application, Serial No. 380,618, filed February 26, 1941.

In the application of Victor L. King referred to above there is described a method for the manufacture of melamine in which a mixture of about 1 part of cyanamide or dicyandiamide with from 1 to 2 parts of liquid ammonia is heated in an autoclave, with or without the addition of anhydrous methanol or other diluents to reduce the autoclave pressure. After the charge has been heated at 100–200° C. for about 2–10 hours in the autoclave it is discharged directly into a body of water, which serves to dissolve out amidines of the type of guanidine and guanylurea that would otherwise contaminate the product. In our copending application, Serial No. 380,618, we described a modification of this process in which an organic hydroxy compound capable of forming a water-soluble iron salt such as tartaric acid, glycerol or mannitol is dissolved in the water into which the autoclave contents are discharged. These compounds prevent the precipitation of iron by the ammonia contained in the autoclave charge and thereby avoid contamination of the melamine product by iron.

The present invention relates to a further improvement in the processes described in the applications referred to above which overcomes the problem of contamination of the melamine by the lubricant used in operating the autoclave. Large-scale operation of the process described in our earlier applications has demonstrated that this is another serious source of contamination of the melamine product, which it is a principal object of the present invention to avoid.

On the accompanying drawing we have illustrated an agitated autoclave of a type that has been used successfully in preparing melamine by the process referred to above. This autoclave consists generally of a heavy, pressure-resisting shell 1 with top and bottom heads 2 and 3 held in place by annular clamping rings 4 and 5, respectively. Proper temperature conditions within the autoclave are maintained by the presence of a series of vertical heating tubes 6, mounted between upper and lower headers 7 and 8 which are provided with inlet and outlet pipes 9 and 55

10 for steam or other suitable heating medium. The autoclave charge is recirculated over these heating elements by means of an agitator 11, driven through a shaft 12 by means of a motor 13 and a suitable gear reduction 14.

The agitator shaft 12 is mounted in a bearing 15 and passes through a stuffing box 16, which is lubricated by a lubricant admitted through a nipple 17 connecting by a line 18 with a suitable reservoir 19. Pressure between the reservoir 19 and the autoclave is equalized by a pipe 20, so that the lubricant flows into the bearing by gravity under a constant hydrostatic head.

When the above-described autoclave was operated in the manner described for the production of melamine we soon discovered that it was necessary to maintain an actual flow of lubricant over the wearing surfaces of the bearing 15 and into the autoclave in order to prevent the deposition of small melamine crystals therein. When a hydrocarbon lubricant was used this infiltration contaminated the melamine formed in the autoclave, and since the subsequent purification step consisted in washing out water-soluble impurities it was impossible to remove the hydrocarbon oil by this method. By applying the principles of the present invention, we have succeeded in overcoming this source of contamination of the melamine and in its preferred form our invention actually improves the subsequent purification step.

We have found that these objects are accomplished by maintaining a flow of a water-soluble lubricant over the bearing 15 instead of the hydrocarbon oil that was formerly used. We have found that adequate lubrication is obtained by employing such compounds as ethylene glycol, glycerine, triethanolamine, Turkey red oil or similar water-soluble compounds of appreciable viscosity as the sole lubricant, and by supplying an adequate flow of a water-soluble material of this class we are able to lubricate the bearing and prevent the deposition of melamine therein while avoiding completely the presence of a hydrocarbon oil as a source of contamination of the melamine.

By employing a water-soluble lubricant we obtain a number of advantages in the melamine manufacturing process. The flow of the lubricant around the bearing 15 does not result in permanent contamination of the product, for the water-soluble lubricant is completely removed in the subsequent washing step in which the contents of the autoclave are drowned in a body of water. For this reason we are enabled

to supply any quantity of lubricant that may be necessary to provide lubrication of the bearing and to prevent the deposition of melamine crystals therein, irrespective of the amounts that may pass into the autoclave. Moreover, when organic hydroxy compounds such as glycol, glycerine, mannitol, polyethylene glycols or mixtures thereof are employed their presence in the autoclave charge actually aids the subsequent washing step, for the hydroxy compound will form a water-soluble complex with any iron that may be present and thereby aid in obtaining an iron-free melamine product.

From the foregoing the process which constitutes our present invention is evident. The manufacture of melamine is carried out in the manner outlined in our two copending applications referred to above, and includes the steps of heating in an autoclave a solution of cyanamide or dicyandiamide in a solvent comprising liquid ammonia while agitating the charge by a rotating agitator and subsequently discharging the contents of the autoclave into a body of water while lubricating the bearing of the agitator shaft by applying thereto a water-soluble lubricant. This lubricant is preferably a polyhydric alcohol of the type of ethylene glycol, polyethylene glycol or glycerine, and our preferred lubricant is glycerine itself. This compound has a surprisingly good lubricating action at temperatures of 100-200° C. on the agitator bearings and has given excellent results as the sole lubricant in large-scale commercial practice. Moreover it is readily soluble in water in all proportions, and the quantities that leak through the bearing into the autoclave are readily and completely removed from the melamine in the subsequent washing step. Since glycerine will form a water-soluble complex with iron compounds its presence in the wash water used in the drowning tank is actually an advantage. The

use of glycerine as a lubricant therefore improves the operation of the process as a whole both by avoiding contamination of the melamine by the hydrocarbon oils ordinarily used for lubricating purposes and by aiding in the removal of iron in the subsequent purification step.

What we claim is:

1. In the manufacture of melamine by a process which includes the steps of heating in an autoclave a solution of a member of the group consisting of cyanamide and dicyandiamide in a solvent comprising liquid ammonia while agitating the charge by a rotating agitator and subsequently discharging the contents of the autoclave into a body of water, the improvement which consists in lubricating the agitator bearing by applying thereto a water-soluble lubricant.
2. In the manufacture of melamine by a process which includes the steps of heating in an autoclave a solution of a member of the group consisting of cyanamide and dicyandiamide in a solvent comprising liquid ammonia while agitating the charge by a rotating agitator and subsequently discharging the contents of the autoclave into a body of water, the improvement which consists in lubricating the agitator bearing by applying thereto a water-soluble lubricant comprising a polyhydric alcohol.
3. In the manufacture of melamine by a process which includes the steps of heating in an autoclave a solution of a member of the group consisting of cyanamide and dicyandiamide in a solvent comprising liquid ammonia while agitating the charge by a rotating agitator and subsequently discharging the contents of the autoclave into a body of water, the improvement which consists in lubricating the agitator bearing by applying thereto a water-soluble lubricant comprising glycerine.
